UNITED STATES PATENT OFFICE.

CLUTAU S. HICKEY, OF FAYETTEVILLE, ARKANSAS.

CLOTH CLAMPING AND STRETCHING MEANS FOR IRONING-BOARDS.

1,368,724.

Specification of Letters Patent. Patented Feb. 15, 1921.

Application filed August 2, 1920. Serial No. 400,754.

To all whom it may concern:

Be it known that I, CLUTAU S. HICKEY, a citizen of the United States, residing at Fayetteville, in the county of Washington 5 and State of Arkansas, have invented certain new and useful Improvements in Cloth Clamping and Stretching Means for Ironing-Boards, of which the following is a specification, reference being had to the accompanying drawings.

The present invention has for its purpose to provide a clamping and stretching device for holding the surface cloth on an ironing board, the aim being to provide means arranged on the underface of the ironing board adjacent the marginal edge thereof and actuated by a single member, for not only holding the cloth in position, but also stretching the same, in order to prevent the cloth from 15 wrinkling or folding in such a manner as to hinder the passage of the iron over the surface of the article which is being ironed or pressed.

The invention still further aims to provide rocking members on the underface of the board adjacent the longitudinal edges thereof and adjacent the curved end edges and provided with cloth attaching means or pegs, in combination with a single 20 actuator operatively connected with the rotating members, for stretching and clamping the cloth.

While the design and construction at present illustrated and set forth is deemed preferable, it is obvious that as a result of a reduction of the invention to a more practical form for commercial purposes, the invention 25 may be susceptible of changes, and the right to these changes is claimed, provided they are comprehended within the scope of what is claimed.

The invention comprises further features and combination of parts, as will be herein-after set forth, shown in the drawings and 30 claimed.

In the drawings:—

Figure 1 is a view in edge elevation of an ironing board, showing the improved stretching and clamping means as applied 35 and illustrating the pressing cloth clamped in position.

Fig. 2 is a bottom plan view of the ironing board, also showing the edge portions of the cloth engaging said rotating members.

Referring to the drawings, 1 designates

a conventional form of ironing board or an ironing laundry press head, and mounted in bearings 2 of the undersurface thereof adjacent its longitudinal edges are rocking rods 3. These rods are provided with radial arms 4. Mounted in bearings 5 on the undersurface of the ironing board adjacent the curved edge of the smaller end of the board are rocking rods 6, which are 60 united to the ends of the rods 3, by means of the couples 7. The couples 7 each comprises a right angle arm 8 having forks 9. These forks 9 straddle the arms 10 of the rods 6. 70

Similar rocking rods 11 are mounted in bearings 12 adjacent the curved edge of the larger end of the ironing board, and are provided with radial arms 13.

Rockably mounted in bearings 14 of the 75 underface of the board in a direction longitudinally of the center of the board is a shaft or rod 15 provided with diametrically opposite radial arms 16 and 17. Links 18 operatively connect the arms 4 and 16 of the 80 rods 3 and 15. In fact the links have lateral extensions 19 pivotally engaging the arms 4 and 16.

A pair of links 20 have their adjacent 85 forked ends 21 straddling the arms 17 of the shaft or rod 15, there being pivot pins 22 passing through the forks and through the arms. The remote ends of the links 20 extend at obtuse angles and have forks 23, which straddle the arms 13. Pivot pins 24 90 pass through the forks 23 and the arms 13, thereby pivotally connecting the parts.

The rocking rods 3, 6 and 11 respectively have hooks 25, 26, and 27, which are engaged by the metallic line openings or eyelets 28 of the pressing cloth 29, which is stretched and clamped over the padding of an ordinary ironing board. The single rod, shaft or operating member 15 has secured thereto a collar 31, which is provided with 100 a handle 32.

It will be noted that by rocking the rod or shaft 15 in the direction of the arrow *a*, the rods 3, 6 and 11 will be moved in the directions indicated by the arrows *b*, thereby pulling the pressing cloth over the edges of the ironing board and stretching the cloth over the surface of the padding, thereby preventing the cloth from wrinkling or becoming folded, which would prevent the 110 passage of the iron over the material being pressed. It will be noted that a clamping

and stretching mechanism of the present character may be easily applied to any suitable pressing supports with many advantages. For instance the pressing cloth may be evenly stretched over the surface, and all parts thereof stretched simultaneously, thereby preventing the cloth from being tensioned or stretched at one place more than the other, and hence avoiding splitting or tearing of the cloth.

Carried by the rocking rod or shaft 14 is a ratchet wheel 30, which is engaged by a spring tensioned dog 33, which is pivotally mounted at 34 on the undersurface of the board, to hold the rocking rod or shaft in its adjusted positions.

The invention having been set forth, what is claimed as being useful is:—

1. In an ironing board cloth stretching and clamping mechanism, the combination with a pressing member, of rocking members upon its undersurface adjacent the side and end edges thereof, and a single means operatively connecting with said members for operating them simultaneously.

2. In a cloth clamping and stretching mechanism, a pressing member, rocking elements mounted in bearings on the undersurface of the pressing member adjacent its longitudinal and end edges, coupling means uniting certain of the rocking members, cloth connecting means on said members, and a single rotating element operatively connected to certain other of the rocking members, for drawing the cloth tight over the surface of the pressing member.

3. In a cloth stretching mechanism, an ironing board, rocking elements mounted in bearings to the undersurface thereof adjacent its longitudinal edges, rocking elements

mounted on the board adjacent its curved end edges, cloth connecting means carried by said rocking elements, with which a pressing cloth engages, means coupling the rocking elements adjacent one end of the board to the rocking elements adjacent the longitudinal edges, and a single actuator carried by the undersurface of the board and being operatively connected to the rocking elements adjacent the other end of the board and to the rocking elements along the longitudinal edges, thereby simultaneously operating said elements and stretching the cloth.

4. In a cloth stretching mechanism, an ironing board, rocking elements mounted in bearings to the undersurface thereof adjacent its longitudinal edges, rocking elements mounted in bearings to the undersurface thereof adjacent its longitudinal edges, rocking elements mounted on the board adjacent its curved end edges, cloth connecting means carried by said rocking elements, with which a pressing cloth engages, means coupling the rocking elements adjacent one end of the board to the rocking elements adjacent the longitudinal edges, and a single actuator carried by the undersurface of the board and being operatively connected to the rocking elements adjacent the other end of the board and to the rocking elements along the longitudinal edges, thereby simultaneously operating said elements and stretching the cloth, and means for holding the actuator in its adjusted positions, to hold the cloth stretched.

In testimony whereof I hereunto affix my signature.

CLUTAU S. HICKEY.
